UNITED STATES PATENT OFFICE.

CHESTER T. SPICKLEMIRE, OF WABANINGO, MICHIGAN.

IGNITION SYSTEM FOR EXPLOSIVE-ENGINES.

1,088,472.

Specification of Letters Patent.

Patented Feb. 24, 1914.

Application filed July 25, 1913. Serial No. 781,198.

To all whom it may concern:

Be it known that I, CHESTER T. SPICKLEMIRE, a citizen of the United States, residing at Wabanningo, in the county of Muskegon and State of Michigan, have invented new and useful Improvements in Ignition Systems for Explosive-Engines, of which the following is a specification.

This invention relates to improvements in ignition systems for explosive engines and has particular application to a reversing switch whereby the engine may be reversed.

In carrying out the present invention, it is my purpose to provide a reversing switch for explosive engines whereby the circuit of the spark plug may be broken so as to decrease the speed of the engine and then subsequently made while the piston is on the up-stroke thereby causing a premature explosion with the result that the direction of rotation of the crank shaft of the engine is reversed. Furthermore, I aim to provide a switch of the class described which will be connected with the control lever of the timer and operable therefrom simultaneously with the timer.

With the above and other objects in view, the invention consists in the construction, combination and arrangement of parts hereinafter set forth in and falling within the scope of the claims.

In the accompanying drawing; Figure 1 is a plan view of a reversing switch constructed in accordance with my present invention. Fig. 2 is a diagrammatic view of an explosive engine ignition system showing my switch installed.

Referring now to the accompanying drawing in detail, the numeral 1 designates an explosive engine of any suitable or preferred form. In the present instance, this engine is of the single cylinder type and is equipped with the usual form of spark plug 2 connected in circuit with the secondary winding of an induction coil I. Connected to one side of the primary winding of the induction coil is a battery 3 or other suitable source of electrical energy, while to the opposite side of such winding is connected the timer 4 of any appropriate construction, the timer grounding the respective side of the battery upon the engine.

The numeral 5 designates my improved reversing switch composed, in the present instance, of a base 6 of some suitable con-

struction and equipped with an appropriate form of bracket whereby the same may be secured to a convenient support. Mounted upon the base 6 and insulated therefrom is a contact 7 to which is connected one terminal 60 of a wire 8 having the free terminal thereof connected to the battery 3. A second contact 8' is also secured to the base 6 and insulated therefrom and spaced apart from the first contact and electrically connected therewith by way of a wire 9. This contact 8' preferably carries a tongue extending toward the contact 7. Fulcrumed upon the base 6 is a bell crank lever 11 having one limb thereof designed to wipe over the contacts 8 and 7 and the opposite limb formed with a series of apertures 12 with which is interchangeably associated one end of a rod 13 having the free end thereof connected to the control lever 14 of the timer 4.

In practice, the spark control lever 14 is retarded and the engine cranked up in the usual manner so that the same will take up its own cycle of operation. When the engine is running in the usual manner and it is desired to reverse the same, the spark control lever 14 is manipulated so as to swing the bell crank lever 11 and disengage the respective limb thereof from the contact 8' and the tongue 10 associated therewith. This breaks the primary circuit and when the speed of the engine has been decreased, the spark control lever is further advanced so that the respective arm of the bell crank lever engages the contact 7. As the primary circuit is closed, incident to the arm of the bell crank lever engaging the contact 7, the circuit of the spark plug 2 is completed and the spark caused as the piston is moving upwardly on the compression stroke. This is, in effect, a premature explosion, and, as a consequence, the direction of movement of the piston is reversed, as is readily understood. When it is desired to again reverse the engine so that the crank shaft will revolve in the usual direction, the control lever 14 is retarded so that the respective arm of the bell crank lever moves out of engagement with the contact 7 whereby the primary circuit is again broken and the engine permitted to slow down.

The speed of the engine, having been sufficiently decreased, the control lever is again retarded so that the respective arm of the bell crank lever rides onto the tongue 110

10 and into engagement with the contact 8' whereby the primary circuit is again made and the spark caused to jump across the terminals of the spark plug while the piston is 5 moving upwardly on the compression stroke, thus causing the direction of movement of the piston and crank shaft to be reversed.

From the foregoing description taken in connection with the accompanying drawing, 10 the construction, mode of operation and manner of employing my invention will be readily apparent. It will be seen that I have provided a manually controlled reversing switch whereby the direction of rotation 15 of the crank shaft of an explosive engine may be reversed without resorting to the use of reversing gear, while the reversing switch and the timer are controlled from a single lever. By means of the tongue 10 on 20 the contact 8' the primary circuit is maintained in the initial movement of the control lever 14 of the timer so that the engine may operate at its usual speed without causing the primary circuit to be ruptured.

25 By means of the adjustable connection between the rod 13 and the respective arm of the bell crank lever of the switch, it will be seen that such bell crank lever may be caused to break and make the primary cir-

cuit at any desired time with respect to the 30 position of the piston within the cylinder.

I claim:

1. In an ignition system for explosive engines, a reversing switch in combination with the primary circuit and comprising a 35 pair of contacts spaced apart and inter-connected, and a bell crank lever having one limb movable over said contacts and connected in said circuit in series with said contacts, and means for swinging said lever. 40

2. In an ignition system for explosive engines, a reversing switch in combination with the primary circuit and comprising a pair of contacts spaced apart and inter-connected, and a bell crank lever having one 45 limb movable over said contacts and connected in said circuit in series with said contacts, means for swinging said lever, and a tongue electrically connected with one of said contacts substantially as, and for the 50 purpose, described.

In testimony whereof I affix my signature in presence of two witnesses.

CHESTER T. SPICKLEMIRE.
